[57] CLAIM

The ornamental design of a grill cleaner, as shown and described.

DESCRIPTION

FIG. 1 is a perspective view of a grill cleaner showing my new design;

FIG. 2 is a front elevational view thereof;

FIG. 3 is an auxiliary end view, the same being taken along the plane 3—3 of FIG. 2;

FIG. 4 is an auxiliary view thereof, the same being taken along the plane 4—4 if FIG. 2;

FIG. 5 is an auxiliary end view thereof, the same being taken along the plane of 5—5 of FIG. 2; and,

FIG. 6 is a top plan view thereof.

The side not illustrated is a mirror image of the side illustrated in FIG. 2.

The broken line showings of a cleaning pad, brush bristles and holes in a scraper blade are for illustrative purposes only and form no part of the claimed design.
